UNITED STATES PATENT OFFICE.

REME A. BEAUSEJOUR, OF NEW YORK, N. Y., ASSIGNOR TO STANDARD VARNISH WORKS, OF NEW YORK, N. Y., A CORPORATION OF NEW YORK.

LIQUID-COATING MACHINE.

No. 921,347.

Specification of Letters Patent.

Patented May 11, 1909.

Application filed January 28, 1907. Serial No. 354,500.

To all whom it may concern:

Be it known that I, REME A. BEAUSEJOUR, a subject of the Crown of Great Britain, and resident of the borough of Brooklyn, in the city and State of New York, have invented a new and useful Improvement in Liquid-Coating Machines, of which the following is a specification.

My invention relates to machines for applying a coat of liquid to an article and has for its principal object to produce a machine that will give a more even coating of the liquid to the article being treated and will prevent what is known in the art as lapping or double coating of the article.

A further object is to provide a machine which will be cheap, durable and simply constructed and which can be easily operated either by hand or power.

20 The machine is also so arranged that the article being coated will be kept free from dust while drying and the coating liquid will be screened at every operation, thus keeping the liquid clean so that it may be used repeatedly.

25 A practical embodiment of my invention is represented in the accompanying drawings in which—

Figure 1 is a view in side elevation partially in section, of a machine suitable for carrying out my invention, Fig. 2 is a front view of the same partially in section, and Fig. 3 is a transverse section taken in the plane of the line A—A of Fig. 2, looking in the direction of the arrows.

In the accompanying drawings I have shown a device consisting of two tanks arranged to be alternately used for coating the articles to be treated. As these tanks are similar in construction I will proceed to describe one only of said tanks.

The tank for receiving the article or articles to be treated is denoted by 1 and it is, in the present instance, made rectangular in form. The cover for the tank is denoted by 2 and it may rest loosely on the open top of the tank or may be secured thereto by any suitable means if so desired. This cover 2 is provided, adjacent to one of the side walls of the tank, with a V-shaped pocket 3, the side of the pocket adjacent to the side wall of the tank being provided with a fine mesh screen 4 through which the coating liquid may flow into the tank. This pocket 3 and screen 4 are so placed that when the coating liquid is

30 poured into the tank, it will be directed against the side wall of the tank and not against the article or articles to be coated.

The means which I have shown for withdrawing the coating liquid from the tank 30 after the article has been treated comprises a series of spigots 5 having suitable cocks 6.

Means are provided for securing the article rigidly within the tank, which means in the present instance is shown as comprising a 35 swinging clamp member 7 and a stationary clamp member 8 arranged to co-act therewith. This swinging clamp member 7 is operated from the exterior of the tank by means of a hand screw 9 arranged in position 40 to have its inner end engaged with the free end of the swinging clamp member. Means are provided for spacing the article to be treated above the bottom of the tank, which means are shown as comprising two serrated 45 ribs 10, 11. For supporting, raising and lowering the tank I provide a cross shaft 12 which is mounted in suitable bearings in brackets 13. On this cross shaft I provide pulleys 14, 15, to which the corresponding 50 upper ends of flexible connections, such as chains, 16, 17, are secured, the lower ends of said chains being secured to hangers 18, 19, loosely mounted on pivots 20, 21, fast to the opposite sides of the tank 1. This arrangement permits the tank to be readily raised and lowered and also to be swung into position for permitting the ready insertion and removal of the articles to be treated. An end chain 22 passes around a sprocket wheel 55 23 fast on the shaft 12 for permitting the manual handling of the tank.

When the machine is composed of a plurality of tanks, the chains from one tank are wound around their pulleys 14, 15, in one 60 direction and the chains from another tank are wound around their pulleys 14, 15, in the opposite direction, so that as one tank is being raised, another tank is being lowered.

Supposing the machine to comprise two 65 tanks as shown in the accompanying drawings, the operation of the same is as follows. The lowered tank is tilted into a position such as that shown in dotted lines in Fig. 1, for permitting the ready insertion of the article to be coated therein. The tank is then 70 swung into its vertical position and its cover 2, with its pocket and screen, 3 and 4, is placed in position over the open top of the tank. One or more of the cocks 6 of the spigots 5 75

may then be opened to permit the coating liquid which is located in the raised tank, to flow into the pocket 3 and from thence through the screen 4 into the lowered tank. 5 This operation will permit the liquid to be gradually withdrawn from engagement with the article being treated in the raised tank and simultaneously gradually permitted to enter the lowered tank to engage the article 10 therein. After the article in the raised tank has become sufficiently dry the raised tank may be lowered into position to permit the removal of the article therefrom, the operation of lowering the raised tank serving to 15 raise the lowered tank to bring it into proper position to fill the other tank with the coating liquid after a new article has been inserted therein.

By this method a very even coating of the 20 article being treated is insured. Furthermore, the thickness of the coating may be varied by the rapidity with which the liquid is withdrawn from its engagement therewith by opening the required number of spigots. 25 Also the articles are protected from dust and dirt while being dried owing to their being entirely inclosed within the tank during this drying period. Furthermore, the coating liquid is screened thoroughly after every 30 operation, thus permitting the coating liquid to be used repeatedly.

While I have shown and described two coacting tanks, it is to be understood that one or more may be used successively, the object 35 of this invention being to provide means for insuring an even coating of the article by the insertion and removal of the coating liquid.

What I claim is:

1. A tank for holding therein an article to 40 be coated, means arranged to introduce a coating liquid into the top and withdraw it from the bottom of the tank while the article is held in the tank and means permitting the tank to be tilted for the insertion and 45 removal of the article.

2. A tank for holding therein an article to be coated, a cover for the tank for completely inclosing the article, means arranged to introduce a coating liquid into the top and 50 withdraw it from the bottom of the tank while the article is held in the tank and means permitting the tank to be tilted for the insertion and removal of the article.

3. A tank for holding therein an article to 55 be coated, a cover for the tank for completely inclosing the article, means arranged to in-

duce a coating liquid into the top and withdraw it from the bottom of the tank while the article is held in the tank and a screen for separating impurities from the 60 liquid while it is being introduced into the tank.

4. A tank for holding therein an article to be coated, a cover for the tank for completely inclosing the article and means arranged to 65 introduce a coating liquid into the top and withdraw it from the bottom of the tank while the article is held in the tank, said cover having a pocket for receiving the liquid as it is introduced into the tank, said pocket 70 having a screen for separating impurities from the said liquid.

5. A tank for holding therein an article to be coated, a cover for the tank for completely inclosing the article, said cover having a 75 pocket provided with a screen for receiving the coating liquid as it is introduced into the tank, and one or more spigots for withdrawing the liquid from the tank while the article is held therein.

6. A tank, means for removably holding an article to be coated therein, means arranged to introduce a coating liquid into the top and withdraw it from the bottom of the tank while the article is held therein and 80 means permitting the tank to be tilted for the insertion and removal of the article.

7. Tanks for holding therein articles to be coated, means for alternately raising and lowering the tanks, means for withdrawing 90 the coating liquid from the bottom of the raised tank and introducing it into the top of the lowered tank and means permitting the tanks to be tilted for the insertion and removal of the articles.

8. Tanks for holding therein articles to be coated, means for alternately raising, lowering the tanks and spigots at the bottoms of the tanks for withdrawing the coating liquid from the bottom of a raised tank and introducing it into the top of a lowered tank and means permitting the tanks to be tilted for the insertion and removal of the articles.

In testimony, that I claim the foregoing as my invention, I have signed my name in 105 presence of two witnesses, this 15th day of January, 1907.

REME A. BEAUSEJOUR.
